UNITED STATES PATENT OFFICE.

GEORGE W. BLAIR, OF PITTSBURG, PENNSYLVANIA.

DESIGN FOR A LAMP-CHIMNEY.

SPECIFICATION forming part of Design No. 26,351, dated December 1, 1896.

Application filed October 31, 1896. Serial No. 610,762. Term of patent 14 years.

To all whom it may concern:

Be it known that I, GEORGE W. BLAIR, of Pittsburgh, in the county of Allegheny and State of Pennsylvania, have invented a new and original Design for Lamp-Chimneys, of which the following is a full, clear, and exact description, reference being had to the accompanying drawings, forming part of this specification, in which—

10 Figure 1 shows in side elevation a lamp-chimney embodying my design. Fig. 2 is a vertical section showing a figured lower part of the lamp-chimney, and Fig. 3 is a similar section of the upper part.

15 The design consists in a lamp-chimney having on its exterior and interior surfaces a pattern substantially as hereinafter described, and shown in the drawings.

20 As shown in the drawings, the lamp-chimney has at its lower portion opposite to the

light a pattern composed of a series of closely-adjacent depressions on one side and a corresponding pattern in reverse on the other side, the depressions on one side of the glass registering with the projections on the other side. ²⁵

The upper part of the chimney is figured with a series of parallel grooves registering with a corresponding series of parallel projections on the interior of the glass, these grooves and projections being longitudinal. ³⁰

I claim—

The design for lamp-chimneys substantially as herein shown and described.

In testimony whereof I have hereunto set my hand.

GEORGE W. BLAIR.
